UNITED STATES PATENT OFFICE.

NEVILLE SMITH AND KENNETH SMITH, OF LONDON, ENGLAND.

CARBURETER.

1,101,345.

Specification of Letters Patent. Patented June 23, 1914.

Application filed October 14, 1912. Serial No. 725,669.

To all whom it may concern:

Be it known that we, NEVILLE SMITH, a subject of the King of Great Britain, residing at 26 Bedford Row, London, W. C., England, and KENNETH SMITH, a subject of the King of Great Britain, residing at 186 Lancaster road, Notting Hill, London, W., England, have invented new and useful Improvements in Carbureters, of which the following is a specification.

This invention relates to carbureters for the production of a mixture of petrol vapor and air for lighting and heating purposes.

It is the object of the invention to provide a carbureter in which the vaporizing surfaces are in contact with water or anti-freezing liquid which maintains them at a uniform temperature and prevents such excessive cooling as would interfere with continued vaporizing; which shall be simple in form and construction; and which shall permit the flow of petrol over a continuous vaporizing surface so that after its first distribution it is at no time resolved into drops.

To this end the invention designs to employ as a vaporizing surface a simple flat metal plate bent into suitably curved zig-zags, so that petrol may be caused to flow in a thin continuous sheet over one side of it, adhering throughout to the surface and nowhere dropping from it.

It is a further object of the invention to provide a carbureter of this class in which the liquid petrol is caused to flow more slowly as it approaches the outlet, and is brought into closer contact with the air, so that the reduction in the rate of vaporization due to cooling of the liquid and partial saturation of the air, may be compensated by the slower travel of the petrol and its closer contact with the air.

The invention further designs to provide in such a carbureter for the circulation of the anti-freezing liquid, so as more perfectly to maintain the desired uniformity of temperature, and for this purpose the most developed construction of carbureter according to the invention includes a stirring device immersed in the anti-freezing liquid.

Constructions according to the invention are illustrated in the accompanying drawings, Figure 1 showing one form in vertical section. Fig. 2 a plan of that form with the cover partially broken away. Fig. 3 a view similar to Fig. 2 of a modification. Fig. 4 a vertical section of the top portion

of the modification shown in Fig. 3 and Fig. 5 is a vertical section of a further modification.

The vaporizing surface is constructed in a very simple and cheap form by bending a flat plate or strip of metal 1 into a series of zigzags. One set of bends 3 of the zig-zags are made comparatively gradual. The zigzags are unequal, the upper ones being much steeper than the lower, as may be seen from the drawing. The plate thus bent is secured within a suitable watertight container 2 which is filled with anti-freezing liquid 10 such as glycerin. This liquid contacts with the plate 1 upon one side, but is shut off from the other side of the plate by a partition 11. The space thus inclosed between the partition 11 and the vaporizing surface 1 is shut in at the top by a suitable cover 18. At the top and bottom of this space provision is made at 13 and 14 for inspection caps. Air is admitted to the vaporizing space through a pipe 7 and hydrocarbon through a pipe 4. This latter conducts the liquid to a distributing device consisting, for instance, of a wedge-shaped channel 5 of wire gauze Fig. 2 lying transversely across the extreme upper end of the vaporizing surface 1. This channel and the surface of the plate 1 adjacent to it are protected from the incoming air by a plate 8 secured to the cover 18 and extending down into close contact with the plate 1. This prevents too rapid vaporization of the petrol upon its immediate entry into the apparatus and permits of its being distributed into a flat sheet before its surface is disturbed by the air.

In order that the air may be thereafter kept in comparatively close contact with the petrol there are provided between successive bends of the plate 1 baffle plates 9 attached to the partition 11 and so arranged as to cause air to flow substantially along the surface of the plate 1 in company with the petrol. The mixed air and petrol is taken from the apparatus at the bottom through a pipe 12.

The gradual curves 3 which constitute the convex bends in the vaporizing surface are such as to permit the petrol to adhere to the surface instead of dropping therefrom. Thus when the apparatus is in operation the whole of the plate 1 becomes covered on one side with a continuous sheet of petrol diminishing to vanishing thickness at the

bottom and thus all the vaporization takes place from a surface which is in contact with the anti-freezing liquid 10. In place of the trough distributor 5 there may be secured upon the upper end of the plate 1 an upstanding slightly bent baffle 6 of wire gauze as indicated in Figs. 3 and 4. The pipe 4 then delivers directly on to the plate 1 and the baffle 6 insures the distribution of the petrol transversely over the plate. The baffle 6 slopes in both directions slightly down the slope of the top plate 1 so that petrol will run from the center outward in contact with the baffle 6 and the petrol will partly pass through the perforations therein all along its length.

In the alternative construction shown in Fig. 5 the plate 1 is curved throughout its length instead of being made up of flat sections with comparatively sharp intermediate bends. A convex vaporizing surface is formed by approximately elliptical bends 15, which however diminish in their minor axis toward the bottom of the apparatus so that the rate of flow of petrol decreases. This modification also illustrates the application of a stirring device to promote circulation of the anti-freezing liquid 10. This consists of suitable blades 16 secured upon a shaft 17 which may be rotated by connection with any suitable portion of the carbureting apparatus, for instance with the pump (not shown) by which air is supplied. The rotation of the blade 16 brings the cold liquid, which is liable to accumulate at the bottom of the casing up toward the surface and so tends to maintain the whole of the liquid, and consequently the whole of the surface 1 at a uniform temperature.

What we claim is:

1. In a carbureter the combination of a flat plate bent into a zigzag, so as to present a number of surfaces of successively decreasing gradient toward the bottom of said zigzag, one side of said plate having convex surfaces of small curvature, a container enclosing said plate, anti-freezing liquid in contact with one surface of said plate, and means for distributing petrol over the other side of said plate and for passing air thereover.

2. In a carbureter the combination of a flat plate bent back and forth so as to present inclined surfaces of successively less inclination, a container surrounding said plate, anti-freezing liquid therein contacting with one side of said plate, means for distributing petrol over the other side of said plate, means for supplying air thereto, and baffle plates between successive bends adapted to keep the air in close proximity to said plate.

3. In a carbureter the combination of a flat plate bent into successive curves substantially semi-elliptical and diminishing in vertical depth, a container about said plate, anti-freezing liquid in said container contacting with one side of said plate at every part thereof, means for supplying petrol and air to the other side of said plate, and means for stirring the anti-freezing liquid.

In testimony whereof we have signed our names to this specification in the presence of two subscribing witnesses.

NEVILLE SMITH.
KENNETH SMITH.
